UNITED STATES PATENT OFFICE.

GEORGE GODDU, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

NAIL-HEAD-SHAPING MACHINE.

1,283,730.

Specification of Letters Patent.

Patented Nov. 5, 1918.

Application filed May 15, 1915. Serial No. 28,344.

To all whom it may concern:

Be it known that I, GEORGE GODDU, a citizen of the United States, residing at Winchester, in the county of Middlesex and 5 State of Massachusetts, have invented certain Improvements in Nail-Head-Shaping Machines, of which the following description, in connection with the accompanying drawings, is a specification, like reference characters 10 on the drawings indicating like parts in the several figures.

The invention to be hereinafter described relates to machines for shaping the heads of nails.

15 In certain machines employing loose nails it is desirable for proper delivery of the nails thereto and the appearance of the work into which the nails are driven, that the heads of the nails shall be of uniform shape and size. To secure this desired end it has been customary during the nail making operations to form the nail heads somewhat larger than desired and then reduce them to uniform size and shape in another machine 20 by forcing them through a die of appropriate design. In such machines the nails, the heads of which were to be shaped, have been taken singly from a source of supply and each nail centered and supported over a die 25 by its head with the body or shank of the nail extending loosely below the die, whereupon the die and a punch were relatively moved toward each other to force the head of the nail through the die.

30 One of the objects of the present invention is to improve a machine of this general character whereby greater uniformity of product may be secured.

An important feature of the present invention 35 consists in means for centering and positioning the shank or body of the nail at the side of the die opposite the nail head to prevent lateral swing of the nail body and cause the nail head to seat squarely on the 40 die as the punch acts upon the head.

Another important feature consists in 45 means for centering the nail head at one side of the die and the shank or body of the nail at the opposite side of the die, thus insuring proper location of the nail head with respect to the die and substantial coincidence 50 of the longitudinal axes of the nail and die.

It is a further object of the present invention to retain the shank or body of the nail

under control of the centering means until 55 the nail head shaping operation has been started, to insure proper directional movement of the nail as the punch forces the head through the die.

Another purpose of the invention is to increase the output of a machine of this general character by simultaneously treating more than a single nail at each operation and to provide means whereby, should an obstruction occur to the proper supply of one 65 nail, it will not prevent the simultaneous supply of another.

Other features of the invention and various improved details of construction will be pointed out by the specification and claims. 70

In the drawings:

Figure 1 is a perspective view of a nail head shaping machine embodying the present invention, some of the parts being broken away for clearness of illustration. 75

Fig. 2 is a side elevation and part sectional view of the machine shown by Fig. 1, some of the parts being omitted and others broken away to disclose parts beyond.

Fig. 3 is an enlarged detail in front elevation, showing more particularly the die, die carrying slide, the upper and lower nail centering jaws and their operative relation. 80

Fig. 4 is an enlarged vertical section of the punch head and the means for adjusting 85 the position of the punch.

Fig. 5 is a perspective view of the upper portion of the eccentric sleeve surrounding the punch carrier.

Fig. 6 is a view similar to that of Fig. 5 90 showing the upper portion of the punch carrier.

Fig. 7 is a perspective of a detached detail, showing the relation of one of the upper and lower nail centering jaws and the 95 die, and illustrating the position of the nail just prior to the head shaping operation.

Fig. 8 is a perspective view on an enlarged scale showing more particularly the end of the raceway, the nail separator, the nail lifter in its lowered position and the relation 100 of the die, the upper and lower centering jaws, punch and nail carriers before a nail is placed in position for the shaping operation.

Fig. 9 is a perspective view looking toward the side and end of the raceway and showing the nail stop and position of the

endmost nail in the series with relation to the stop and nail lifter prior to the action of the nail separator.

Fig. 10 is a detached perspective view 5 of the die carrier and die.

Fig. 11 is a perspective view looking from substantially the same view-point as in Fig. 9 but showing the lifter in raised position and the nail carriers taking a nail from the 10 lifter, and illustrating also the relation of the centering jaws, die, and punch with respect to the lifter and carriers.

Fig. 12 is a view similar to that of Fig. 11 but showing the nail as having been taken 15 by the carriers and placed in position between the punch and the die, some of the parts being broken away.

Fig. 13 is a view similar to that of Fig. 12, but showing the nail carriers as having released the nail and the latter as held in the 20 upper and lower centering jaws and die as these parts and the punch relatively move in the direction of approach.

Fig. 14 is a view similar to that of Fig. 13, 25 but showing the upper centering jaws as having released the nail and the punch acting upon the nail head.

Fig. 15 is a similar view showing the final 30 position of the parts, as the punch forces the nail head through the die and just prior to the return of the parts to the position shown by Fig. 8.

Fig. 16 is a perspective view of the lower 35 centering jaws which grasp between them and hold the body of the nail below the head until the punch starts the nail head through the die, the jaw carrying arms being broken away.

Fig. 17 shows the nail as it may appear 40 before having its head shaped in the present machine, and

Fig. 18 is a similar view showing the same nail after its head has been shaped.

The machine frame may be of any desired 45 character, and in the present instance is shown as comprising a standard 1 having secured thereto by bolts 2, the head frame 3. Mounted on the head frame 3 is the shaft 4, which may be rotated from any 50 convenient source of power, and in the present instance said shaft is provided with fast and loose pulleys 5 and 6 for coöperation with a driving belt.

Nails, the heads of which are to be shaped, 55 are supplied to the machine from suitable hoppers, which, in the present instance, are of the rotary type, and since the present invention contemplates the simultaneous treatment of two nails, two of such hoppers 7 and 8 are provided. The hoppers 7 and 8 are suitably mounted on the head frame and may be conveniently rotated from the back shaft 9 through gearing connection therewith, one part 10 of such connection being 60 illustrated in Fig. 1. The back shaft 9 is

supported in suitable bearings 11, Fig. 1, on the head frame, and may be driven from the shaft 4, as by the belt connection 12.

Extending from each of the hoppers 7 and 8 is a raceway 13 which receives nails 70 from its associated hopper for delivery to the nail head shaping means to be herein-after described. The upper end of each raceway has a portion 14 on to which nails are dropped as the hoppers are rotated and 75 in order to prevent clogging of the nails and facilitate their travel down the raceway, the upper receiving portion of each raceway is preferably agitated from time to time by suitable means. In the present instance such 80 means consists of a hammer 15 for each raceway pivotally supported at 16 and normally under the influence of a spring 17 tending to depress the free end 18 of the hammer into contact with the upper portion 85 of its associated raceway. Secured to the head frame is a bracket 19 carrying a bearing 20 for a shaft 21 which may be rotated by any suitable means, such as the belt and pulley connection 22, 23 and 24 90 from the back shaft 9, Fig. 1. The shaft 21 carries a hammer lifter 25 adapted to act upon the hammers to lift them as the shaft rotates and then permit them to respond abruptly to the action of their springs 95 17 thereby to strike the end portions of the raceways and agitate the nails resting thereon.

The raceways are of the type wherein the 100 nails are supported by their heads with the shanks or bodies of the nails extending into the slots of the raceways and it is intended that the nails while thus supported shall travel to the delivery end of each raceway. To remove nails from the raceway 105 which fail to take the described position and arrange the nails in proper order in the raceway, there is provided for each raceway a rotary toothed member 26, the teeth of which pass sufficiently close to the top of the raceway to prevent the passage of nails not properly positioned and yet permit the passage of those which are properly supported by their heads upon the raceway. Rotary motion may be imparted to said toothed 110 members by appropriate means, which in the present instance, comprises gearings 27 and 28 operatively connecting the shaft 21 with the rotary toothed members. As the improperly positioned nails are thrown from 115 the raceways, they pass into chutes or troughs 29 one for each raceway, and may be returned to the hoppers. Each raceway has a cover 30, which serves to prevent nails 120 properly positioned in the raceway from being dislodged as they travel downward therein, and such cover is provided at the delivery end of its associated raceway with a guide portion 31, Figs. 1 and 9, for a purpose that will presently appear. 130

As the nails are delivered at the ends of the raceways, the present invention contemplates that they shall be taken therefrom successively and presented to the nail head shaping means, which in the present form of the invention consists of a punch and die. The means for carrying into effect this feature of the present invention may be variously formed, and as shown comprises a lifter adapted to take the endmost nail from each raceway and raise it to a position to be engaged by nail carriers which thereupon take control of the nails and place them in position between the punches and dies. A good practical form of this feature of the present invention will now be described.

Mounted in suitable guideways in the machine head 3 is a lifter slide 32, Figs. 2 and 11, which is reciprocated in its supporting guides by appropriate means. In the illustrated form of the invention said means comprises a rack 33 formed as part of or connected to the lifter slide 32, and a toothed segment 34 carried by an arm 35 mounted to rock about an axis 36, and having a roller 37 engaged by an appropriately shaped cam 38 on the shaft 4, the construction being such that upon rotation of the shaft 4 the arm 35 will cause the lifter 32 to be reciprocated in its guides.

The lifter 32 reciprocates in a path between the end of the raceways and the nail head shaping means and is provided with a slot 39 for the passage of nails, as indicated in Fig. 11. Secured to the lifter slide at each side of the slot 39 is a cap piece 40, the adjacent end portions of which are provided with nail head passages 41, Figs. 9 and 12, to accommodate the head of a nail delivered from the associated raceway. These cap pieces are removably secured to the lifter slide by bolts 42, or other suitable means, so that they may be readily changed to provide a passageway 41 suitable to the heads of the nails to be treated.

In order that the end nail of the series in each raceway may be properly delivered to the lifter 32 and the remaining nails be prevented from leaving the raceways or interfering with the nails in the lifter as the latter rises to position the nails for the nail carriers, there is provided a nail stop and a nail separator for each raceway, and as one is or may be the same as the other, a description of one will be sufficient for a proper understanding of this feature of the invention. The nail stop 43 is adjustably secured to an appropriate support, which, in the present instance, is the end portion of the adjacent raceway, by bolt and slot connections 44, 45, Fig. 8, and extends through the slot 39 of the lifter, Fig. 9.

Mounted for movement in suitable transverse guideways 46 at the end of the raceway, is a nail separator 47, Figs. 8 and 9,

pivotedly connected by the pin 48 to an arm 49 pivoted at 50, Fig. 2, to the head frame and carrying a roller 51 in operative engagement with a cam 52, the construction and timing of parts being such that when the lifter is in its low position ready to take a nail from the series, the nail separator is moved forward to insure that the end nail of the series shall be taken by the lifter and the remaining nails be pushed back in the raceway to provide clearance between the head of the nail in the lifter and those yet in the raceway. To secure these objects more effectively the separator 47 has a beveled end portion as at 53, Fig. 9, to act upon the nails in the raceway as the separator moves forward, as described. The separator 47 is provided with a slot 54 through which passes the pivot pin 48, and a spring 55, Fig. 8, connected to the arm 49 and separator 47 as indicated in Fig. 8 normally acts to retain the separator and arm in the relation illustrated but permits the separator to yield against the action of the spring should any unusual obstruction be presented to its forward or separating movement.

As hereinbefore stated the end nails in the two raceways are delivered to the lifter and such nails hang in the lifter by their heads which are engaged in the nail head passages of the lifter. As the lifter rises it is desirable that the body of the nail in the lifter be prevented from swinging movement and to this end the raceway covers are provided with the guides 31, hereinbefore described, which extend from the top of the raceway and are adapted to counteract any swinging tendency of the nails as they are raised by the lifter to position for the action of the nail carriers.

The nail head shaping means in the present form of the invention comprises a punch and a die which have relative movement in a plane at one side of the lifter. It therefore becomes necessary after the nails to be treated have been taken from the raceways by the lifter to transform them into position between the punch and die. This operation is performed by nail carriers, which constitute an important feature of the present invention and a particular form of which will now be described in connection with the duplex machine illustrated.

Mounted for rocking movement about an axis or shaft 56 supported by the head frame 3, Figs. 1 and 2, is a yoke 57 carrying at its lower portion two carrier arms 58, each of which has adjustably secured thereto by suitable means, such as the bolts 60, Figs. 3 and 8, a carrier jaw 59. The yoke 57 has an extension 61 to which is connected at 62 a rod 63, which is itself jointed at 64 to an arm 65 pivotally mounted at 66 in the head frame, and having connected thereto for movement therewith an arm 67 carrying a

roller 68 in operative engagement with a suitably shaped cam 69 mounted on the shaft 4. The construction last described is such that upon rotation of the shaft 4 the yoke 57 and perforce its two carrier arms and carrier jaws will be rocked about the axis 56 as a center. The two carrier jaws 59 are appropriately positioned in separated relation so that as one engages a nail presented 10 by the lifter from one raceway or supply, the other will be caused to similarly engage the other nail presented by the lifter from the other raceway. Each of the carrier jaws 59 has an end portion notched as at 70, Fig. 8, and appropriately shaped to embrace the shank or body of the nail in the lifter below the head of the nail, as will more fully appear.

Each of the nail carrier jaws 59 is associated with a coöperating nail carrier jaw 71 each mounted upon a carrier arm 72, Figs. 1 and 2, loosely supported by the shaft 56 for rocking movement thereon. Mounted on the shaft 56 to rock therewith are the 25 arms 73, one for each carrier arm 72, and one of which is provided with an upward extension 74 connected at 75, Fig. 2, to an actuating rod 76 which may be operated from the shaft 4 by suitable connections, such as the 30 rocker arms 77 and 78 mounted for rocking movement together about the axis 66 under the action of a roller 79 and cam 80 of appropriate form.

The carrier arms 72 and the arms 73 are 35 connected for relative yielding movement, and as one means to this end the carrier arms 72 are each provided with a slot 81, Figs. 1 and 2, which is engaged by a pin 82 projecting from one of the arms 73, an appropriate spring being provided for normally holding the said arms in the relative position indicated by Fig. 2. A convenient form of such spring is illustrated in Figs. 1 and 2, as having a portion 83 coiled about the shaft 56 45 with the free ends of the spring engaging lugs 84 and 85 on the arms 73 and 72 respectively, the construction being such that said springs normally retain the pins 82 in the outer end portions of the slots 81 and 50 cause said arms to move in unison under normal working conditions, but should either of the carrier arms 72 be abnormally obstructed in its movement, as by a misplaced nail, the spring will permit said arm 55 to yield without interfering with the normal operation of the other arm 72. The nail carrier jaws 71 are each provided with a recess 86 to receive and hold the head of a nail presented to it by the lifter.

60 The construction and relation of the parts for taking the nails from the lifter and transferring them to a position between the punch and die are such that as the lifter reaches its top position the carrier jaws 59 65 are first moved toward the lifter to position

the slotted end portions 70 of said jaws in recesses 87 of the lifter caps, Fig. 11, to insure the reception of the nail body in the slots 70 of the carrier jaws 59. Thereupon, or simultaneously with such movement of the 70 carrier jaws 59, the carrier jaws 71 are moved toward and into the slotted portion of the lifter to engage the heads of the nails and move them forward into the slots 70 of the jaws 59. The two nails are now held 75 between the two pairs of jaws 59 and 71, whereupon said pairs of jaws are moved simultaneously from the position of Fig. 11 to that of Fig. 12, to place the nails between the punches and dies. 80

Should one of the carrier jaws 71 meet with an abnormal obstruction, such as a misplaced nail in the lifter, it will yield under the action of the spring before described, and not prevent the other lifter jaw 71 from co-operating with its companion jaw 59. Thus means are provided in a duplex machine for normally presenting two nails to the nail head shaping means, and under abnormal obstruction to the presentation of one nail to 90 permit the other to be properly presented. 85

The nails being now transferred to a position between the punches and dies, the present invention further aims so to position or center the nails laterally and longitudinally 95 with relation to the axes of the punches and dies, that when the nail heads are forced through the dies they shall be properly shaped. To secure this result and a uniformity of product the body or shank of the 100 nail should be centered or positioned uniformly with relation to the axis of the die through which it is forced, and the head should be correspondingly centered and positioned on the die. It is desirable also that 105 when the punch meets the nail to force it through the die the centered relation of the longitudinal axis of the die and the nail should remain undisturbed. These conditions and the resulting uniformity of product are secured by the present invention as 110 will now be more fully set forth.

In the present form of the invention, relative movement of the punches and dies is secured by reciprocating the dies toward and 115 from the punches, and as one appropriate means to this end the head frame 3 is provided with guideways for a slide plate 88, which will be hereinafter called the die slide. These guideways may be conveniently 120 formed by the plates 89, 89 overlapping the edge portions of the die slide 88, Figs. 1, 2 and 3, and secured to the head frame by suitable means, such as the bolts 90. The die slide 88 may be reciprocated by any suitable 125 means, and in the present instance, it is provided with rack teeth 91, Fig. 2, operatively engaged by a toothed segment 92, carried by an arm 93 pivotally sustained at 36 and having a roller 94 engaged by a suitable cam 95 130

secured to rotate with the shaft 4, the construction being such that as the shaft 4 rotates the die slide 88 will be reciprocated in its guideways on the head frame.

5 The die slide 88 carries two dies, one for each of the nails, the heads of which are to be shaped, and since said dies, their coöperating punches and nail centering and positioning means, are similar in construction 10 and operation a description of one set will be sufficient for a full understanding of these features of the invention.

The die consists of a body or carrier 96 secured to the die slide by means of suitable 15 bolts 97 and a covering plate 98, Figs. 1 and 3. The die carrier 96, Fig. 10, is provided with a shoulder 99 and in the present instance the die plate 100 is secured to the carrier 96 to provide between the shoulder 99 20 and die plate a space or opening for a purpose hereinafter explained. As one means of securing this relation of the die plate and carrier, the latter is provided with a block 101 having a centering pin 102 for engaging 25 a slot or opening 103 in one edge of the die plate, and corner posts 104 to which the die plate is detachably secured by suitable means, such as the screws 105. The die plate 100 has an opening 106 which constitutes the 30 die proper through which the heads of the nails are forced by the punch to shape and size them. If desired, a pin 107 may be employed to assist in properly locating and holding the die plate in position on the die 35 carrier.

As hereinbefore noted the present invention aims to position the nail with respect to the die and punch in such manner that the head will be centered upon the die and the 40 body of the nail will be centered and held from sidewise movement as the punch meets or acts upon the nail. These effects are secured by nail head engaging and centering means at one side of the die, and nail body 45 engaging and centering means at the opposite side of the die, a good practical form of which comprises upper and lower centering jaws which engage the nail head and body respectively and then successively release the head and body as the punch meets and acts upon the nail.

Pivottally mounted upon the die slide 88 at 108, Fig. 3, is the arm 109 carrying at its upper end the plate 110 provided with a 55 centering jaw 111, closely superjacent to the die, Figs. 11, 12 and 13. Similarly pivottally mounted to the die slide 88 at 112, Fig. 3, is an arm 113 carrying at its upper end the plate 114 provided with a companion centering 60 jaw 115 above the die, the meeting jaws 111 and 115 forming between them when closed a seat for the head of a nail for centering and positioning the nail head above the die.

The two upper jaw carrying arms 109 65 and 113 are normally held in closed relation

by means of a spring 116, Figs. 1 and 2, but are adapted to be opened as the punch meets the head of a nail centered in the jaws. To this end the arm 109 is extended below its pivotal connection 108 with the die slide and 70 carries a roller 117 which is caused to travel along a cam 118 as the die slide reciprocates by means of a spring 119 extended between the arms 109, Figs. 2 and 3. In order that both jaws of the upper centering means may 75 be moved to open and close them, the arms 109 and 113 are connected for movement simultaneously in opposite directions. A good form of connection for this purpose is 80 shown in Fig. 3, wherein each of the arms 109 and 113 is provided with engaging segment teeth 120.

From the construction of the upper centering jaws and their operative relation as thus far described, it will be noted that 85 as the nail is transferred from the lifter to a position between the punch and die or has about reached this position, as in Fig. 12, the die slide starts to rise carrying the upper centering jaws with it, and when, or 90 about the time, the nail passes into the upper centering jaws and the die, the nail carriers separate, Fig. 13, permitting the nail to drop and the nail head *a* to rest in the upper centering jaws as indicated in Fig. 13. The 95 nail now hangs by its head from the upper centering jaws with its body portion loosely suspended within the die. The die slide continues to rise and when, or just before, the punch meets the head of the nail the cam 100 118 opens the upper centering jaws and permits the head of the nail to rest upon the upper or entering portion of the die. Owing to irregularities in the nail head where it rests upon the die or to the vibration of the 105 machine or other causes, the body of the nail is liable to swing to one side in the die and thus disturb the centered position of the nail head on the die with the result that as the punch forces the nail through the die, 110 the proper shape will not be imparted to the head. This invention therefore provides means to center and hold the body of the nail at the side of the die opposite the nail head until the punch has started to force the head 115 through the die, as will now be explained.

The die slide has secured thereto, as by bolts 121, Figs. 1, 2, 3 and 11, the blocks 122, one at each side thereof for the pivotal support of lower centering jaws, and as said 120 block and lower centering jaws for each side of the die slide are similar the following description of one will be sufficient to make this feature of the invention clear.

Pivottally mounted at 123 and 124 on the 125 block 122 are the lower centering jaw carriers 125, each provided with a clamp 126 and bolt 127 for adjustably securing thereto the lower jaws 128, the active end portions of which are turned toward each other at 130

129 to extend into the opening or space between the shoulder 99 of the die carrier and the die plate 100 to engage and center the body portion of a nail at the side of the die 5 opposite the upper centering jaws. The in-turned end portions 129 of the lower or nail body centering jaws are provided with complementary recesses 130 forming guiding surfaces and an opening to direct the pointed 10 end of the nail between the jaws as the nail assumes the position indicated in Figs. 1 and 13.

The lower jaw carriers 125 have portions 131, Figs. 3 and 11 normally under the influence of a spring 132, which tends to separate the portions 131 and maintain the lower jaws normally in closed relation, and to insure corresponding movements of the lower jaws as they are opened and closed. The two lower jaw carriers are provided with engaging toothed segments 133 and 134. It is desirable that the toothed segments be related to cause their teeth to be properly engaged and that one jaw be adjustable relatively to the other jaw to enable the opening between the jaws to be centered in line with the die, and to this end one of the toothed segments, the segment 134 in the present instance, is formed independently of the jaw carrier 125 and the pivot stud 124 has an eccentric portion 135, Fig. 11, on which the sleeve of the toothed segment 134 is mounted so that by turning the pivot stud 124 the toothed segment may be bodily moved toward or from the segment 133 and the teeth of the segments be operatively positioned as desired. The sleeve of the toothed segment 134 is secured to the lower jaw carrier 125 by means of a clamp 136 and set screw 137 and is preferably formed with an eccentric lower portion, the construction being such that by loosening the clamp 136 the sleeve may be turned with relation to the jaw carrier and stud 124, thus adjusting the jaw carrier 125 to properly center the opening 130 of the lower jaws under the die.

From the construction described as one good practical form of the lower or nail body centering means, it will be seen that as the nail assumes the position with its head 50 *a* between the upper centering jaws, Figs. 7 and 13, the body portion of the nail will extend through the die 106 beneath the upper centering jaws, and into the opening between the ends of the lower centering jaws beneath the die. As the die and punch 55 continue to approach, the upper or head centering jaws separate, as in Fig. 14, to permit the head of the nail to rest upon the top of the die, but the lower centering jaws still continue to embrace the shank or body 60 of the nail to prevent lateral swing thereof as the punch acts upon the nail head. When, however, the punch has initiated movement 65 of the nail head through the die or has engaged the nail head with sufficient force to

insure against any tilting or swinging movement of the nail body, it is desirable that the lower centering jaws be opened to permit the nail to pass through the die and into a suitable chute or receptacle after its head has been shaped. 70

Various forms of means may be employed for thus opening the lower centering jaws, but since the centering jaws above the die first release the head of the nail and thereafter the centering jaws below the die release the body of the nail, the present invention aims to open the lower centering jaws by the opening movement of the upper centering jaws. As one means to this end the lower jaw carriers 125 are each provided with a cam portion 138 at the jaw side of their pivotal mounting, which are adapted to be engaged by a part connected to one of the upper jaw carriers as the latter moves to open the upper jaws. In the present instance, the upper jaw carrier plate 110, Figs. 11, 12, 13, 14 and 15, has projecting therefrom a pin or stud 139, which, as the upper centering jaws are opened, as hereinbefore explained, passes between the cam portions 138 of the lower jaw carriers and opens the lower centering jaws, the relation of parts being such that the pin or stud thus acts upon the cam 138 after the upper centering jaws have started to open, as indicated in Fig. 14, and the head of the nail has been met by the punch.

The punch is adjustably mounted in the head frame so that the longitudinal axes of the punch and die may be readily brought into alinement. As a preferred form of construction, the punch 140, Fig. 4, is provided with a conical head 141 adapted to be received in a correspondingly shaped socket or seat in a punch holder 142 and held therein by appropriate means, such as the stem 143, which may be threaded to the punch head and extend longitudinally of the punch holder beyond its end opposite the punch where it may receive a nut 144. The punch is eccentrically mounted in the holder 142 with respect to its longitudinal axis, and the barrel portion of the punch holder 142 is mounted in the opening 145 eccentrically formed with respect to the longitudinal axis of the sleeve 146. The punch holder may be held in the sleeve 146 by any suitable means, but in the present instance it is provided with a shoulder 147 which engages the lower end of the sleeve and is held adjustably therein by means of lock nuts 148 threaded to the upper end 149 of the holder 142 and overlying a portion of the upper end of the sleeve, Fig. 4.

The sleeve 146 has a head portion 150 to rest upon the top of the split clamp 151 supported by the head frame and a threaded lower portion to receive a suitable nut 152. In order that the sleeve may be adjusted ro-

tatably in the clamp 151, the flange portions of the split clamp are provided with bolts 153 which may be loosened when desired to permit the sleeve to be adjusted and then 5 set up to hold it in adjusted position.

The sleeve 146 and its head 150 are also split longitudinally as at 154 and 155 and may be further partially split at 156 and 157 to clamp the punch holder in place and yet 10 permit the punch holder to be rotatably adjusted in the eccentric opening 145 of the sleeve. From the construction described it will be apparent that the punch 140 is under adjustment control of two eccentrically related parts, whereby it may be readily 15 brought into exact alinement with the die and then be held rigidly in place.

Metal chips are liable to accumulate about the die and interfere with the proper action 20 of the nail centering means or prevent proper positioning of the nail in the die. In the present invention an air blast is caused to play upon the die and adjacent parts to remove the chips. Such air blast is provided by an air conduit 158, Fig. 1, leading from a pump 159, which may be conveniently operated from the shaft 4 by means of a rod 160 connected to an eccentric 161 or other operating element on the shaft 4. 25 The air from the pump and conduit is passed to the head frame of the machine and is directed upon the parts from an opening or exit 162, Fig. 2.

The operation of the machine has been 30 pointed out during the description of the parts and their associated relations and further elucidation thereof is not necessary, but the character of the work done may be made more clear from Figs. 17 and 18, the former 35 of which shows the general form of the heads *a* of nails supplied to the machine for treatment, while the latter shows the condition and general shape of the nail heads after being treated in the present machine. 40 Nails of the character represented by Fig. 17 are supplied to the hoppers of the present machine and taken from the raceways by the lifter which is adapted to engage and lift 45 two nails, one from each raceway, from a position Fig. 9 to that of Fig. 11 to be engaged by the nail carriers which transfer the nails from the position Fig. 11 to that of Fig. 12 between the punches and dies. 50 Thereupon the die slide rises and when the pointed ends of the nails have entered the centering jaws and dies, the carrier jaws separate, Fig. 13, letting the nail heads rest in the centering jaws above the die and the body of the nails in the centering 55 jaws below the die. Upon further upward movement of the die slide and centering jaws carried thereby, the centering jaws above the die separate, Fig. 14, letting the heads of the nails seat themselves upon 60

the dies, whereupon the punches engage the 65 heads of the nails and start them through the dies. The upper centering jaws continue to separate as the die slide rises and when the punches have exerted sufficient pressure upon the nail heads to insure 70 proper directional movement of the heads through the dies, the lower centering jaws separate to permit the passage of the nails through the dies.

In order that the nails, the heads of which 75 have been shaped, may be properly collected by suitable receptacles unmixed with chips, each die holder 96 is connected to a tubular chute 163 which passes through a piece of packing 164, such as felt or the like, sustained upon a chip receiving pan or shelf 165 supported from the head frame, Fig. 1. These tubular chutes 163 also extend through the pan or shelf 165 and move up and down through the packing as the die slide is reciprocated, the result being that while the metal chips may fall upon the pan or shelf 165 they are precluded from falling into the nail receiving receptacle beneath.

Having thus described the invention, what 90 is claimed as new and desired to be secured by Letters Patent of the United States is:—

1. In a machine for shaping the heads of nails, the combination of a punch and a die constructed and arranged for the passage of 95 a nail parallel to its longitudinal axis, nail head centering means for engaging the head of a nail at one side of the die and positioning it with respect to the die, and nail body centering means for engaging and positioning the body of the nail at the opposite side of the die.

2. In a machine for shaping the heads of nails, the combination of a punch and a die, nail head centering means for engaging the 105 head of a nail at one side of the die and positioning it with respect to the die, nail body centering means for engaging and positioning the body of the nail at the opposite side of the die, and means for successively 110 releasing the head and body of the nail from the centering means.

3. In a machine for shaping the heads of nails, the combination of a punch and a die, means for relatively moving them to shape 115 the head of a nail, nail body centering means for engaging the body of the nail after the same has entered the die and positioning it at the side of the die opposite the nail head entering portion, and means for causing the 120 nail body centering means to release the body of the nail after the punch has engaged the head of the nail.

4. In a machine for shaping the heads of nails, the combination of a punch and a die, 125 and means for positioning the nail for the shaping operation comprising jaws at one side of the die for engaging and positioning

the head of the nail, and jaws at the opposite side of the die for engaging and positioning the body of the nail.

5. In a machine for shaping the heads of 5 nails, the combination of a punch and a die, means for relatively moving the punch and die, centering jaws for engaging the head of a nail at one side of the die for positioning the nail head, centering jaws for engaging 10 the body of the nail at the opposite side of the die for positioning the nail body, and means for successively opening the nail head centering jaws and nail body centering jaws as the punch and die are relatively 15 moved.

6. In a machine for shaping the heads of 20 nails, the combination of a punch and a die, two pairs of nail centering jaws, one above and the other below the die for engaging and positioning the head and body of a nail respectively, and means for operating one pair of jaws by movement of the other.

7. In a machine for shaping the heads of 25 nails, the combination of a die, means for delivering a nail endwise into said die, a punch for pushing the nail through the die to shape the head thereof, and a pair of centering jaws for engaging the body of the nail at that side of the die opposite the side 30 at which the nail enters the die to center the nail with reference to the die during a portion of the relative movement of the die and the punch.

8. In a machine for shaping the heads of 35 nails, the combination of a die adapted to receive and support a nail by its head, a punch for pushing a nail through the die for shaping the head of the nail, means for delivering a nail to the die, a pair of centering jaws for engaging and positioning the body of a nail the head of which rests upon the die, and means for releasing the body of the nail from the centering jaws during relative movement of the punch and 45 die.

9. In a machine for shaping the heads of 50 nails, the combination of a die to receive and support a nail by its head, a punch for pushing the nail through the die for shaping the head of the nail, a pair of independently supported centering jaws movable in opposite directions toward the plane of the die opening for engaging and positioning the body of a nail the head of which is to be shaped, and means for releasing the body of the nail from the said centering jaws after the punch has engaged the head of the nail.

10. In a machine for shaping the heads of 60 nails, the combination of a die adapted to support a nail by its head, a punch, means for reciprocating the die to cause the punch to force the nail through the die, and nail centering means movable with the die for

engaging and positioning the body of a nail 65 at that side of the die opposite the nail head entering portion.

11. In a machine for shaping the heads of 70 nails, the combination of a die for supporting a nail by its head, nail centering jaws for engaging and positioning the body of a nail at that side of the die opposite the nail head supporting portion, means for opening and closing the centering jaws, and means for adjusting said jaws to align them with 75 the opening in the die.

12. In a machine for shaping the heads of 80 nails, the combination of a punch and a die, upper centering jaws for engaging and positioning the head of a nail above the die, means for opening and closing said jaws, lower centering jaws for engaging and positioning the body of the nail below the die, and means operated by movement of the upper centering jaws for opening the lower 85 centering jaws to release the body of the nail.

13. In a machine for shaping the heads of 90 nails, the combination of a punch, a die carrier having a die supported thereby to provide an opening extending transversely below the die, said carrier being movable relatively to the punch to cause a nail to be forced through the die, means for delivering a nail into said die, lower centering jaws, and means for causing them to engage and 95 position the body of the nail in the opening below the die.

14. In a machine for shaping the heads of 100 nails, the combination of a punch, a die support carrying a die, means for relatively moving the punch and die, centering jaws for engaging and positioning the head of a nail at one side of the die, and centering jaws for engaging and positioning the body of a nail at the opposite side of the die, said 105 head engaging and body engaging jaws being mounted on the die support.

15. In a machine for shaping the heads of 110 nails, the combination of a punch, a slide carrying a die, means for reciprocating the slide, centering jaws for engaging the head of a nail above the die, centering jaws for engaging and positioning the body of a nail below the die, and means for mounting said centering jaws for movement with the die 115 carrying slide.

16. In a machine for shaping the heads of 120 nails, the combination of a punch and a die, centering jaws at one side of the die for engaging and positioning the head of a nail, centering jaws at the opposite side of the die for engaging and positioning the body of a nail, said last named jaws being provided with cam portions, and means connected to the head centering jaws for acting on said 125 cam portions to open the body centering jaws.

17. In a machine for shaping the heads of

5   nails, the combination of a punch and a die, means for centering the head of a nail above and with relation to the die, centering jaws, for engaging and positioning the body of a nail at the side of the die opposite said head centering means, means for relatively moving the punch and die to shape the head of a nail centered in the die, and means for releasing the body of the nail from the centering jaws after the punch has engaged the head of the nail.

10   18. In a machine for shaping the heads of nails, the combination of a punch and a die, means for supplying nails the heads of which are to be shaped, a nail carrier for taking a nail from the supplying means and placing it between the punch and die comprising two relatively and conjointly movable arms, and positive means for relatively operating said 20 arms to take a nail from the supplying means, one of said arms being mounted for yielding movement relative to the other.

15   19. In a machine for shaping the heads of nails, the combination of a plurality of punches and dies for simultaneously shaping the heads of a plurality of nails, means for supplying nails for the action of the punches and dies comprising a plurality of nail carriers each including a pair of carrier arms, 25 a common actuator for said pairs of carrier arms to cause each pair of arms to take a nail from a source of supply and place it between a punch and die, one of the carrier arms of each pair being yieldingly mounted.

20   20. In a machine for shaping the heads of nails, the combination of a pair of punches and a pair of dies for simultaneously shaping the heads of two nails, a lifter for taking two nails from a source of supply and 40 lifting them opposite the space between the punches and dies, a pair of nail carriers for each nail presented by the lifter, actuating means for moving the carriers of each pair to take the nails from the lifter and place 45 them between the punches and dies, and means for permitting one of the carriers of each pair to yield independently of the corresponding carrier of the other pair when it meets an abnormal obstruction.

25   21. In a nail head shaping machine, the combination of a punch and a die, a lifter for taking a nail from a source of supply and lifting it to a position opposite the space between the punch and the die, nail carrier 55 arms having nail engaging jaws, operating means for positively moving said nail carrier arms both relatively and in unison to cause said jaws to engage a nail between them and take it from the lifter, and means 60 for yieldingly connecting one of the nail carrier arms with said operating means.

30   22. In a nail head shaping machine, the combination of a punch and a die, a lifter for taking a nail from a source of supply and 65 presenting it opposite the space between the

punch and the die, nail carrier arms having nail engaging jaws, positive means for operating said arms both relatively and in unison, and a spring connection between one of said arms and the operating means to permit 70 said arm to yield when an obstruction is presented to its movement.

35   23. In a nail head shaping machine, the combination of a pair of punches and a pair of dies, a yoke having two nail carrier arms 75 connected thereto and carrying nail engaging jaws, means for positively operating said yoke, two opposed nail carrier arms and jaws cooperating with the nail carrier arms and jaws connected to the yoke, and means for 80 yieldingly operating said two opposed nail carrier arms and jaws that they may yield independently when movement of either is obstructed.

40   24. In a nail head shaping machine, the combination of a punch and a die, a lifter provided with a slot for the passage of a nail therethrough and a recessed top portion, a pair of carrier jaws, one of which is adapted to pass through and push a nail from said 90 lifter and the other of which is arranged to enter the recessed top portion of the lifter in position to receive the nail before it is pushed from said lifter by the opposite carrier jaw, and means for operating said 95 jaws.

45   25. In a machine for shaping the heads of nails, the combination of a punch and a die, a raceway for supplying nails the heads of which are to be shaped, a stop to arrest the 100 endmost nail, a lifter for taking the endmost nail and raising it to a position opposite the space between the punch and the die, and a nail separator movable transversely of the raceway for pushing the nails upward in the 105 raceway from the endmost nail to provide clearance for the endmost nail as it is raised by the lifter.

50   26. In a machine for shaping the heads of nails, the combination of nail head shaping 110 means, a raceway having a cover provided with an upwardly extended nail guiding portion above the end of the raceway, and a lifter for engaging and carrying a nail upward in front of the nail guiding portion of 115 said raceway cover.

55   27. In a machine for shaping the heads of nails, the combination of nail head shaping means, a raceway, a lifter for taking a nail from the raceway and lifting it, a stop for 120 the endmost nail presented by the raceway, and a guide extending above the end of the raceway a sufficient distance to prevent the nail from falling from the lifter as the lifter rises to its uppermost position. 125

60   28. In a machine for shaping the heads of nails, the combination of nail head shaping means, a raceway, a lifter for taking a nail from the raceway and lifting it, a stop for 130 the endmost nail presented by the raceway,

- 5 a guide extending above the end of the race-way to prevent the nail from falling from the lifter as the latter rises, and a nail separator constructed to push the nails upward
10 5 in the raceway and the end nail into the lifter to provide clearance between the head of the nail in the lifter and the nails in the raceway and between the head of the nail in the lifter and the said guide as the lifter rises.
- 15 29. A die for shaping the heads of nails, comprising a die carrier having a shoulder, a die plate having a die opening for the passage of nails, and means for supporting the die plate above the shoulder to provide a space between the die plate and shoulder.
- 20 30. A die for shaping the heads of nails comprising a die carrier having a shoulder, a die plate having a die opening for shaping the heads of nails, blocks interposed between the die plate and shoulder to provide a space between the plate and shoulder, and means for securing the die plate to said blocks.
- 25 31. In a machine for shaping the heads of nails, the combination of a die slide carrying a die, means for operating it, nail head centering jaws pivotally mounted on the die

slide, connections between said jaws to cause each of said jaws to move when one of them is moved to open or close the jaws, and means for operating one of said jaws by movement of the die slide.

32. In a machine for shaping the heads of nails, the combination of a punch, a die slide carrying a die, means for reciprocating the die slide, a tubular chute connected to the die to carry nails the heads of which have been shaped out of the machine, and a packing through which the tubular chute reciprocates to prevent chips passing with the nails to the point of delivery.

33. In a machine for shaping the heads of nails, the combination of a punch, a die slide carrying a die, means for reciprocating the die slide, a chip pan to receive chips formed during the nail head shaping operation, a tubular chute connected to the die and passing below the chip pan, and a packing between the chip pan and tubular chute to prevent chips passing to the point of delivery of the nails, the heads of which have been shaped.

In testimony whereof I have signed my name to this specification.

GEORGE GODDU.
